UNITED STATES PATENT OFFICE

161,584

STACK BINDER SHEET FOR DISPLAYS OF CANS, JARS, AND THE LIKE, ARRANGED IN STACKS

Robert W. Johnson, Santa Ana, Calif.

Application July 6, 1948, Serial No. 147,409

Term of patent 14 years

(Cl. D80—5)

To all whom it may concern:

Be it known that I, Robert W. Johnson, a citizen of the United States, residing at Santa Ana, in the county of Orange and State of California, have invented a new, original, and ornamental Design for a Stack Binder Sheet for Displays of Cans, Jars, and the like, arranged in stacks, of which the following is a specification, reference being had to the accompanying drawing forming part thereof, in which:

Fig. 1 is a top perspective view showing a corner portion of a stack binder sheet, showing my new design.

Fig. 2 is an edge view of the corner portion shown in Fig. 1 as viewed from the lower left of Fig. 1; and

Fig. 3 is a top plan view of a corner portion of the stack binder sheet of my new design shown in Fig. 1.

I claim:

The ornamental design for a stack binder sheet for displays of cans, jars, and the like, arranged in stacks, as shown.

ROBERT W. JOHNSON.
